UNITED STATES PATENT OFFICE.

OSCAR VAN TASSELL, OF PARKERSBURG, IOWA.

FEED-STEAMER.

SPECIFICATION forming part of Letters Patent No. 225,892, dated March 23, 1880.

Application filed July 15, 1879.

To all whom it may concern:

Be it known that I, OSCAR VAN TASSELL, of Parkersburg, in the county of Butler and State of Iowa, have invented a new and Improved Grain or Feed Steamer, of which the following is a specification.

Figure 1 is a sectional side elevation in line *x x*, Fig. 2. Fig. 2 is a transverse sectional elevation on line *y y*, Fig. 1.

10 Similar letters of reference indicate corresponding parts.

The object of this invention is to provide a novel steam-generator for heating and dampening wheat in flour-mills, for steaming feed 15 for farm purposes, &c.

The invention consists in a grain and feed steamer consisting of a cylindrical shell, heads provided with double rings, screw-rods provided with beads and nuts, semicircular fire- 20 box provided with vertical face, and sloping plate, door-frame, hot-air flues, stack, doors, grate, supply-pipe, and steam-pipe; also, in a combination of a semicircular fire-box provided with vertical face and sloping plate, and 25 the flues provided with return bends, all as hereinafter described.

In the drawings, *A* represents the cylindrical shell of the generator or boiler; *B*, the cast-iron heads, provided on their inner faces with 30 the double raised rings *C*, that form between them a deep annular groove, into which the cylinder-edges are fitted.

When the cylinder and heads are set together proper packing is interposed to make 35 the joints steam-tight.

40 D are the screw rods or bolts, furnished with heads *a'* and nuts *b'*, that hold the heads to the cylinder by passing through them along the outside of the cylinder, and having their nuts tightly turned down.

E is a fire-box of semicircular cross-section at the front of the boiler, and continuing so for three-quarters, or thereabout, of its length, when its flat upper surface turns at a right 45 angle abruptly upward for a short distance, forming a vertical face, *F*, and then again as abruptly rearward in a horizontal line to the top of the door-frame *G*, in the rear boiler-head, while the lower curved surface of the 50 fire-box terminates in a semicircular plate, *H*, that slopes upward to the lower edge of the door-frame *G*, thus forming a narrow throat

between the sloping face of the plate *H* and the angle made by the upward turn of the top of the fire-box.

55 Through the vertical face *F* are entered the hot-air tubes or flues *I*, that extend forward for some distance in the water-space of the boiler, then turn upward and rearward, making a return bend, and are made to project 60 some inches through the rear head of the boiler into the smoke-stack or bonnet *K*; or they may terminate in the boiler-head, if it be thought desirable.

The door *L* may be fitted into the door-frame 65 *G* as shown, or it may be hinged to the door-frame in the usual manner. On its removal the lower tubes can be easily cleaned and air admitted to assist in the combustion of the smoke and gases, while the upper tubes can 70 be cleaned on removal of the smoke-stack.

The fire-box is provided with a removable grate, *M*, and a door, *N*.

O represents the supply-pipe of the boiler, and *P* the steam-pipe.

In ordinary practice a steam-dome is set 75 upon the boiler, which may also be provided with the usual safety-valve, steam-gages, &c., and the boiler is set on legs or frame, as convenient, and it is constructed with one or more 80 hot-air flues or tubes, as may be desirable.

Having thus described my invention, what I claim as new, and desire to secure by Letters Patent, is—

1. The within-described steam-generator, 85 consisting of the cylindrical shell *A*, heads *B*, provided with double rings *C*, screw-rods *D*, provided with heads *a'* and nuts *b'*, semicircular fire-box *E*, provided with vertical face *F* and sloping plate *H*, door-frame *G*, hot-air 90 flues or tubes *I*, bonnet or stack *K*, doors *L* and *N*, grate *M*, supply-pipe *O*, and steam-pipe *P*, constructed and arranged substantially as herein shown and described.

2. The combination, in a steam-generator, 95 of a semicircular fire-box, *E*, provided with vertical face *F* and sloping plate *H*, and the flues or tubes *I*, provided with return bends, substantially as herein shown and described.

OSCAR VAN TASSELL.
